TRAFFIC SIGNAL

John J. Hammer, Detroit, Mich.

Application September 22, 1938, Serial No. 231,127

4 Claims. (Cl. 177—337)

This invention relates to traffic signals of the type used to control the flow of traffic at the intersection of streets and highways.

One object of this invention is to provide a Stop and Go signal for use at the intersection of streets and highways adapted to positively inform pedestrians and motorists respectively whether or not sufficient time remains to cross an intersection before the Go signal changes to Stop.

Another object of the invention is to provide a traffic signal for use at intersections of streets and highways in which a warning of a light change from green indicating Go to red indicating Stop is accomplished by a traveling light moving around the green Go light first appearing as a yellow light and then changing to a red light after traveling partly around the green Go light.

Another object of the invention is to provide a Go and Stop traffic light for use at intersections of streets and highways which removes the uncertainty of how long a green Go light will stay green which will enable pedestrians and motorists to avoid entering an intersection on the green Go light too late to fully cross the intersection before the green Go light changes to the red Stop light whereby to free intersections of traffic hazard to pedestrians and motorists and increase the capacity of the intersection to handle traffic because of being clear of pedestrians and vehicles at each change of the traffic light.

Another object of the invention is to provide a traffic signal having a green Go light and a red Stop light and simple and inexpensive mechanism for changing the said signal from Go to Stop and Stop to Go.

Another object of the invention is to provide a traffic signal having a green Go light, a red Stop light and a warning light showing pedestrians and motorists respectively of the change of the green Go light to a red Stop light having only a single large lens facing each direction which will avoid confusion in interpreting signals, the said traffic signal being lighted by a single cluster of lamps for all colored lights which definitely avoids failure in the operation of the signal lights unless all of the electric lamps in the lamp cluster burn out at once.

Another object of the invention is to provide a novel and improved traffic signal having green Go lights appearing in opposite directions simultaneously with red Stop lights appearing in opposite directions 90 degrees with respect to the said green Go lights including a warning light

traveling around each of the said green Go lights which first appears as yellow and then turns to red whereby to provide separate warnings to pedestrians and motorists timed proportionate to their relative speed of travel along the highway that the green Go light is about to change to the red Stop light.

Another object of the invention is to provide a traffic signal light composed of an outer square housing having clear lenses on all sides thereof, an inner housing mounted for 90 degrees arcuate reciprocation about its vertical center within said outer housing having green Go and red Stop lenses therein disposed at 90 degrees with respect to each other, and illuminating means within said inner housing for throwing light through all green and red lenses whereby to make green Go signals and red Stop signals appear through the said clear lenses, means for arcuately reciprocating said housing 90 degrees responsive to timing means whereby to change signals appearing through the said clear lenses from green Go to red Stop and vice versa, and a warning signal traveling around each green signal appearing first as yellow and later as red timed for giving pedestrians and motorists respectively sufficient warning proportionate to their relative speed of travel along the highway when it is too late to start to cross an intersection protected by said traffic signal before the said green Go signal changes to a red Stop signal.

Another object of the invention is to provide a traffic signal light composed of an outer housing having main clear lenses on all sides thereof, an inner housing mounted for 90 degrees arcuate reciprocation about its vertical center within said outer housing having pairs of oppositely disposed green Go and red Stop lenses therein disposed at 90 degrees with respect to each other, illuminating means within said inner housing for throwing light through all green and red lenses whereby to make green Go signals and red Stop signals appear through the said main clear lenses, means for arcuately reciprocating said inner housing 90 degrees responsive to timing means whereby to change signals appearing through the said main clear lenses from green Go to red Stop and vice versa, and small warning lights disposed under the said main lenses responsive to timing means for giving warning that the said green Go signals will change to red Stop signals.

Other objects of the invention will become apparent by reference to the following detailed

description taken in connection with the accompanying drawings, in which:

Fig. 1 is an elevational view of a traffic signal embodying the invention having portions thereof broken away to indicate the green Go lens and traveling yellow and red warning lenses thereof.

Fig. 2 is an enlarged detailed vertical sectional view taken on the line 2—2 of Fig. 1.

Fig. 3 is a fragmentary plan view showing means for arcuately reciprocating the colored lens carrying inner housing of the novel traffic signal about its vertical center.

Fig. 4 is a horizontal sectional view of the inner arcuately reciprocating lens carrying unit taken on the line 4—4 of Fig. 2.

Fig. 5 is an elevational view of the traveling warning light Stop switch and cam therefor.

Fig. 6 is a detailed sectional view taken on the line 6—6 of Fig. 5.

Fig. 7 is a wiring diagram relating to the operation of the traffic signal disclosed in Figs. 1 to 5 inclusive.

Fig. 8 is an elevational view showing another embodiment of the invention wherein fixed warning lights are substituted for the traveling warning lens of the embodiment of the invention disclosed in Figs. 1 to 7 inclusive.

Fig. 9 is an enlarged vertical sectional view taken on the line 9—9 of Fig. 8.

Referring now to the drawings wherein like numerals refer to like and corresponding parts throughout the several views, the embodiment of the invention disclosed in Figs. 1 to 7 inclusive comprises a preferably square outer housing 10 having a single large clear lens 11 suitably mounted in each side thereof, a preferably square inner housing 12 centrally disposed within the said outer housing 10 mounted for 90 degrees arcuate reciprocation on and about its vertical axis having a pair of oppositely disposed green lenses 13 in two sides thereof and a pair of oppositely disposed red lenses 14 located at 90 degrees with respect to the said green lenses 13 in the other two sides thereof, the said green lenses 13 and the said red lenses 14 being centered with respect to the clear lenses 11 in the outer housing 10. The said green lenses 13 are each fixed in the center of a vertically disposed rotatable annular opaque disc 15 which has a single circular yellow lens 16 mounted through the face thereof, the said opaque disc 15 being centrally mounted in a ring gear 17 which is preferably rotatably supported on a plurality of pinions 18 and rotated by a motor 19, through a speed reducer 20 and drive pinions 21 keyed on each end of oppositely turning drive shafts 22 and 220 extending from the said speed reducer 20. The entire drive mechanism for rotating the ring gears 17 is supported from the base 23 of the inner housing 12.

Inasmuch as each green lens 13 is centrally mounted in an annular opaque disc 15 having a yellow lens 16 mounted therethrough adjacent the said green lens 13, the said green lens appears stationary when the said opaque disc 15 is rotated on an axis central with respect to the said green lens 13 and normal to the face thereof, however, the yellow lens 16 appears to travel around the said green lens 13 during the rotation of the said opaque disc 15. The said yellow lens 16 in each of the annular opaque discs 15 is normally positioned at the bottom of the green lens 13 when the green lenses 13, opaque discs 15 and ring gears 17 are not in rotation.

Illuminating means preferably composed of a

cluster of electric lights 24 is centrally supported and located within the said inner housing 12 for projecting light through the green lenses 13 in the inner housing 12 which shows a green Go light through oppositely disposed clear lenses 11 in the outer housing 10 and for projecting light through the yellow lens 16 in each of the said opaque discs 15 in which the said green lenses 13 are mounted showing a yellow light through each of the said clear lenses in the outer housing 10 which travels around the said green light when the opaque disc 15 is rotated. The said yellow light traveling around the green light serves as a warning to pedestrians that the green light will not remain lighted a sufficient length of time to permit pedestrians to cross an intersection protected by a traffic signal embodying the invention before the green Go light changes to a red Stop light and before traffic in a cross direction is given the green Go signal. An opaque fixed shield 25 is disposed in front of each of the opaque discs 15 at the bottom of the said inner housing 12 behind which the said yellow lenses 16 are positioned when no warning signal is being given. A vertically disposed arcuate stationary red lens 26 is positioned between the illuminating means 24 and each opaque disc 15 extending arcuately counter clockwise from the bottom center of the inner housing 12 to any desired segment of a circle, for example 90 degrees. The said red lenses 26 serve to change the color of the yellow warning light to red during the latter portion of its travel around the green light for the purpose of giving a separate warning to motorists that the green light will not remain lighted sufficient time for a vehicle to cross an intersection protected by a traffic signal embodying the invention before the green Go light changes to a red Stop light and before traffic in a cross direction is given the green Go light.

The said illuminating means 24 also project light through the red lenses 14 in the inner housing 12 which show a red Stop light through the oppositely disposed clear lenses 11 in the outer housing 12 located at 90 degrees with respect to the clear lenses 11 through which the hereinbefore described green Go and traveling yellow and red warning lights appear. A suitable hood 110 is provided around each of the clear lenses 11 to prevent signal lights projected therethrough from being confused by pedestrians and motorists in lanes of traffic in cross directions to each signal.

Traffic signals embodying the invention may be supported on a suitable post or suspended from an overhead arm or cable as may be desired. The embodiment of the invention disclosed in Figs. 1 to 7 inclusive is of the supported type and is constructed with a centrally disposed collar 27 depending from its outer housing 10 which telescopes into the top of a hollow supporting post 28 and is secured therein by such suitable means as one or more anchorage studs 29.

A circular base 30 is suitably fixed in the depending collar 27 of the said outer housing 10 onto which the inner housing 12 is preferably mounted for arcuate reciprocation about its vertical center within the said outer housing 10 by means of a mounting sleeve 31 secured to the bottom of the base 23 of the said inner housing 12 by machine bolts 32. The said mounting sleeve 31 is preferably bored and counterbored to receive the outer races of thrust type ball bearings 33 and 34, the inner races of which are

preferably telescoped over a vertically disposed stationary stub shaft 300 integral with and extending centrally upward from the said circular base 30. The inner race of the lower thrust type ball bearing 34 is supported on the said circular base 30.

The said inner housing 12 is arcuately reciprocated on its vertical axis within the said outer housing 10 by means of spaced arcuate solenoids 35 and 36 which are secured to and supported from the outer housing 10 on suitable sleeve type brackets 37 clamped securely around the said solenoids 35 and 36. The solenoids 35 and 36 have a common arcuate core 38 therethrough which is secured at its center through and to a tongue 39 bracketed radially outward from the said mounting sleeve 31 of the said inner housing 12. When the solenoid 35 is energized, the arcuate core 38 fixed to the mounting sleeve 31 of the inner housing 12 is drawn by the magnetic field of the solenoid 35 to the position indicated in Fig. 3 which turns the inner housing 12 to the position shown in Fig. 2. When the solenoid 36 is energized, the arcuate core 38 fixed to the mounting sleeve 31 of the inner housing 12 is drawn by the field of the solenoid 36 centrally into the said solenoid and turns the said inner housing 12 90 degrees with respect to its former position with the tongue 39 extending radially outward from the mounting sleeve 31 positioned as indicated by the dot and dash lines 390 in Fig. 3 whereupon the inner housing 12 and the signal lights carried thereby is positioned 90 degrees with respect to the position thereof indicated in Fig. 3. Thus by alternately energizing the solenoids 35 and 36, the inner housing 12 and the signal lights carried thereby is arcuately reciprocated 90 degrees about its vertical center with respect to the outer housing 10 and the signal lights appearing through the clear glass lenses 11 in the outer housing 10 change from green Go to red Stop and vice versa. A spring loaded ball detent 40 adapted to become engaged in notches 41 and 42 disposed at 90 degrees with respect to each other in the mounting sleeve 31 or other suitable equivalent means eliminates wobble as the inner housing 12 is reciprocated about its vertical center by the arcuate solenoids 35 and 36.

A stop switch 43 as indicated in Figs. 5 and 6 is mounted on one wall of the inner housing 12 and is operated by a switch lever arm 44 carrying a roller 45 which is constantly urged against the side of one of the annular ring gears 17 by such means as the spring 440. The stop switch 43 is normally closed, however, it is opened and held open by a cam 46 so located on the side of the said ring gear 17 as to open the said stop switch 43 when the ring gears 17 are rotated to a position in which the yellow lenses 16 carried by the opaque discs 15 are behind an opaque fixed shield 25. Figs. 5 and 6 show the said stop switch lever arm 44 raised by the cam 46 to a position at which the said stop switch 43 is open. A spring loaded brake 190 adapted to be released by the solenoid 1900 preferably mounted on the slow speed pinion shaft 220 sets whenever the cam roller 45 rides the cam 46 and opens the said stop switch 43 and stops the motor 19 and the rotation of the ring gear 17.

Suitable time control means of any well known standard type and construction, not shown but indicated diagrammatically in Fig. 7 and which is not a part of the instant invention, may be used to energize the various circuits of the novel traffic signal disclosed herein. A common conductor 47

is connected from a source of electric energy to the motor 19, to the brake release solenoid coil 1900 of the brake 190, to the illuminating means 24, and to the solenoids 35 and 36, all as indicated in the wiring diagram Fig. 7. Any well-known type of drum controller 70 such as indicated in Fig. 7 rotated at the desired speed may be employed. The said drum controller 70 may be rotated in the direction indicated by the arrow 11 10 by any suitable means such as a synchronous motor, not shown. The said drum controller 70 is provided with a continuous contact strip 4900 therearound which is continuously energized through the contact finger F490 and the conductor 490 which is connected to a source of electrical energy, the said conductor 490 also being connected to the switch 43 through which current is supplied to the motor 19 after it has started running by current supplied thereto 15 through the conductor 49 as hereinafter described. Contact strips 499, 3600 and 3500 suitably disposed on the surface of the drum controller 70 are all cross connected to the live continuous contact strip 4900 and each energizes conductors 49, 360 and 350 respectively through suitable contact fingers F49, F360 and F350 respectively in the proper sequence as hereinafter disclosed and is obvious by reference to the drum controller 70; thus a standard type drum control means is 20 adapted to energize the arcuate solenoid 35 through the conductor 350 and the arcuate solenoid 36 through the conductor 360 alternately for several seconds at the desired time intervals which causes the timed arcuate reciprocation of the 25 inner housing 12 of the traffic signal disclosed in Figs. 1 to 7 inclusive, the switch diagrammatically indicated by a circle designated by the numeral 48 in Fig. 7 causing the illuminating means 24 to be lighted through the conductor 240 at all 30 times except when the inner housing 12 is being moved arcuately 90 degrees in either one direction or the other by the said solenoids 35 and 36. The said switch 48 diagrammatically indicated 35 within the circle 48 in Fig. 7 has 5 contactors. 40 Contactor A is connected to one side of the solenoid 35. Contactor B is connected to conductor 350, contactor C is connected to the light bank 24, contactor D is connected to the conductor 360, and contactor E is connected to the one side of the solenoid 36. Contactors B and D are fixed, contactor C is movable by the movement of the inner housing 12, and contactors A and E are movable responsive to the movement of contactor C. The movement of the contactor C in one direction breaks the normally spring closed contactors A and B and the movement of the contactor C in the other direction breaks the normally spring closed contactors D and E. 45 When the inner housing 12 is turned to the position indicated in Fig. 2 by the solenoid 35, the tongue 39 through which the arcuate core 38 of the solenoid 35 and 36 is fixedly mounted engages the bifurcated end 480 of the contactor C and moves the same to the left as viewed in Fig. 7 50 whereupon contactors A and B are opened, contactors B and C are closed, and contactors D and E are closed. 55 Also, when the inner housing 12 is turned 90 degrees by the solenoid 36, the said tongue 39 moves the contactor C to the right from the position indicated in Fig. 7 whereupon contactors A and B will be closed, contactors B and C will be opened and contactors C and D will be closed. When the contactor C is moved to the left as 60 shown in Fig. 7 by the turning of the inner hous- 65

ing 12 to the position shown in Fig. 2, energy is applied to the light bank 24 through the conductor 47 directly from the source of electric energy and through the conductors 240 and 350, the said conductor 350 picking up its energy from the finger F350 on the drum controller 70. As the drum controller revolves the contact finger F49 comes in contact with the contactor strip 499 which energizes the solenoid brake release coil 1900 and starts the motor 19 through the conductor 49 causing the ring gear 17 carrying the yellow lens 16 to start revolving. As the ring gear 17 revolves the switch 43 is caused to close by the cam roller 45 running off the cam 46.

The closing of the switch 43 energizes the motor 19 directly from the source of power S—S through conductors 47 and 490 and the motor continues to run until the cam roller 45 again rides the cam 46 and opens the switch 43 which stops the rotation of the motor 19 and the rotation of the ring gear 17 by de-energizing the solenoid brake release coil 1900. Immediately after the said switch 43 becomes opened by the cam 46 the drum controller 70 breaks the current running through the conductor 350 and supplied current through the conductor 360.

As soon as the circuit 360 is energized the solenoid 36 is energized and turns the inner housing 90 degrees which causes the contact C of the switch 48 to be moved from left to right by the arcuate movement of the tongue 39 causing contactors B and C to be opened, contactors A and D to be closed, contactors D and E to be opened, and contactors C and D to be closed. In this second position of the contactor C, the light bank 24 is energized through the conductor 47 directly from the source of electric energy and through the conductors 240 and 360, the said conductor 360 picking up its energy from the finger F360 on the drum controller 70. The contactors A and B are now closed so that the solenoid coil 35 may be energized as soon as another contact strip 3500 is contacted by the finger F 350 of the drum controller 70 which will turn the inner housing 12 in the direction opposite to the direction in which it had just previously been turned, this after the ring gear 17 carrying the yellow lens 16 has been caused to revolve as hereinbefore described by the conductor 49 again being energized by the finger F49 contacting another contact strip 499 on the drum controller 70.

Thus, the time control means 70 applies energy to the motor 19 and the brake release solenoid 1900 through the conductor 49 for several seconds at the desired time at which the yellow pedestrian traveling warning signal appears prior to a change of light from green to red which starts the motor 19 and causes the ring gear 17 to rotate whereupon the warning light stop switch 43 closes when the roller 45 of the switch arm 44 thereof rides off the cam 46 on the said ring gear 17. When the warning light stop switch 43 is closed, the time control means 70 then cuts off the current supply through the conductor 49 to the motor 19 and brake release solenoid 1900 after first connecting the current supply to the motor 19 and brake release solenoid 1900 through the conductor 490 and the warning light stop switch 43. The motor 19 continues to run until the warning signal carried by the ring gear 17 makes one complete revolution whereupon the cam 46 kicks out the said warning light stop switch 43 and the motor circuit including the solenoid brake release circuit is instantly de-energized causing the ring gear 17 to stop rotating at such a

position that the warning lens 16 in the opaque disc 15 mounted in the said ring gear 17 comes to a stop behind the fixed shield 25 which obscures the said warning light until the next time 5 the warning light circuit is energized. After the warning light comes to a stop behind the said shield 25, the said time control means 70 then immediately energizes the proper circuit 350 or 360, as the case may be, whereupon the main traffic signal lights change from green Go to red Stop and vice versa.

Figs. 8 and 9 disclose a traffic signal similar in every respect to the embodiment of the invention disclosed in Figs. 1 to 7 inclusive except that the traveling warning light and all mechanism relating thereto has been omitted and the outer housing 10 has been changed to a deeper outer housing 100 to accommodate small fixed yellow warning lights 50 and 51 disposed directly below the main clear lenses 11 in the said outer housing 100. The use of the fixed warning lights 50 and 51 necessitates the lengthening of the sole- 15 noid supporting brackets 37 to high brackets 370 as indicated in Fig. 9 and has required the circular base 30 on which the inner housing 12 is mounted to be extended upwardly by inserting an extension 301 between the said circular base 30 and the spindle 300 as shown in Fig. 9. The green lenses 13 are preferably the same size as the red lenses 14 and are fixed in the side of the inner housing 12.

The embodiment of the invention shown in Figs. 8 and 9 is otherwise identical to the embodiment of the invention hereinbefore described in detail and shown in Figs. 1 to 7 inclusive, the change of signals from green Go to red Stop and vice versa being accomplished by the arcuate reciprocation of inner housing 12 by means of the novel arcuate solenoid mechanism embodying the invention.

The time control means required to operate the embodiment of the traffic signal disclosed in Figs. 8 and 9 and the wiring diagram required is obviously similar to that described for the embodiment of the invention disclosed in Figs. 1 to 7 inclusive with the exception that the circuit used to operate the motor 19 and the solenoid 1900 and the stop switch 43 is omitted and that two circuits energized from the time control means 45 are substituted therefor, the said circuits being employed to light the warning lights 50 and 51 a predetermined time prior to the change of the signal thereabove from green Go to red Stop.

Although the disclosure and description refers 55 to square traffic signals and 90 degree operation thereof, it is obvious that the shape of the outer housings 10 and 100 may be altered to any reasonable number of sides at any reasonable angle with respect to each other to adapt the said signal 60 to serve at other than 90 degree intersections of streets and highways and at intersections where two or more streets or thoroughfares intersect or meet.

Although but one embodiment of the invention 65 and one modification thereof has been disclosed and described herein it will be observed that various changes including the size, shape, arrangement and details of the various parts thereof may be made without departing from the spirit of the invention and it is not intended to limit the scope thereof other than by the terms of the appended claims.

I claim:

1. A traffic signal light comprising a fixed outer housing, a clear lens in each side of the said outer

housing, an inner housing mounted for arcuate reciprocation within said outer housing about the vertical center thereof, green and red lenses alternately disposed one in each side of said inner housing horizontally centered with respect to the said clear lenses in said outer housing, said green lenses being mounted for rotation about their horizontal center, a yellow lens, fixed radially adjacent each green lens, timing means, means responsive to said timing means for rotating said green lenses about their horizontal center whereby to cause said yellow lenses to travel around the center of said green lenses, illuminating means in said inner housing adapted to project light through said green, red and yellow lenses whereby to present green Go, red Stop and yellow Warning signals through said clear lenses, a shield adapted to obscure said yellow Warning signals when not traveling around the center of the said green signals, and means responsive to said timing means for reciprocating said inner housing on a sufficient arc about its vertical center whereby to change the green lenses horizontally centered on said clear lenses to red lenses and to change red lenses horizontally centered on said clear lenses to green lenses which simultaneously changes all green Go signals presented to red Stop signals and vice versa at the completion of the travel of the said yellow Warning signal around the center of each green Go signal.

2. A traffic signal light comprising a fixed outer housing, a clear lens in each side of the said outer housing, an inner housing mounted for arcuate reciprocation within said outer housing about the vertical center thereof, green and red lenses alternately disposed one in each side of said inner housing horizontally centered with respect to the said clear lenses in said outer housing, said green lenses being mounted for rotation about their horizontal center, a yellow lens fixed radially adjacent each green lens, to timing means, means responsive to said timing means for rotating said green lenses about their horizontal center whereby to cause said yellow lenses to travel around the center of said green lenses, illuminating means in said inner housing adapted to project light through said green, red and yellow lenses whereby to present green Go, red Stop and yellow Warning signals through said clear lenses, a shield adapted to obscure said yellow Warning signals when not traveling around the center of the said green signals, means responsive to said timing means for reciprocating said inner housing on a sufficient arc about its vertical center whereby to change the green lenses horizontally centered on said clear lenses to red lenses and to change red lenses horizontally centered on said clear lenses to green lenses which simultaneously changes all green Go signals presented to red Stop signals and vice versa at the completion of the travel of the said yellow Warning signal around the center of each green Go signal, and a red lens disposed in the path of light through each yellow lens at the latter arc of its travel around the center of each green lens whereby to change the yellow Warning signal to a red Warning signal just prior to the change of all green Go signals to red Stop signals and vice versa.

3. A traffic signal light comprising a fixed outer housing, a clear lens in each side of the said outer housing, an inner housing mounted for arcuate reciprocation within said outer housing about the vertical center thereof, green and red lenses alternately disposed one in each side

of said inner housing horizontally centered with respect to the said clear lenses in said outer housing, opaque discs rotatably mounted in alternate sides of said inner housing, each disc having one of said green lenses centrally mounted therein, a yellow lens mounted in each disc radially adjacent the green lens therein, timing means, means responsive to said timing means for rotating said discs which causes the said yellow lenses to travel around the center of the said green lenses, illuminating means in said inner housing adapted to project light through said green, red and yellow lenses whereby to present green Go, red Stop and yellow Warning signals through said clear lenses, a shield adapted to obscure said yellow Warning signals when not traveling around the center of the said green signals, means responsive to said timing means for reciprocating said inner housing on a sufficient arc about its vertical center whereby to change the green lenses horizontally centered on said clear lenses to red lenses and to change red lenses horizontally centered on said clear lenses to green lenses which simultaneously changes all green Go signals presented to red Stop signals and vice versa at the completion of the travel of the said yellow Warning signal around the center of each green Go signal, and a red lens disposed in the path of light through each yellow lens at the latter arc of its travel around the center of each green lens whereby to change the yellow Warning signal to a red Warning signal just prior to the change of all green Go signals to red Stop signals and vice versa.

4. A traffic signal light comprising a fixed outer housing, a clear lens in each side of the said outer housing, an inner housing mounted for arcuate reciprocation within said outer housing about the vertical center thereof, green and red lenses alternately disposed one in each side of said inner housing horizontally centered with respect to the said clear lenses in said outer housing, said green lenses being mounted for rotation about their horizontal center, a yellow lens disposed radially adjacent each green lens, timing means, means responsive to said timing means for rotating said green lenses about their horizontal center whereby to cause said yellow lenses to travel around the center of said green lenses, illuminating means in said inner housing adapted to project light through said green, red and yellow lenses whereby to present green Go, red Stop and yellow Warning signals through said clear lenses, a shield adapted to obscure said yellow Warning signals when not traveling around the center of the said green signals, means responsive to said timing means for traveling the said yellow Warning lens around said green Go lens prior to the changing of the presenting of a green Go signal to a red Stop signal through said clear lenses, and means responsive to said timing means for reciprocating said inner housing on a sufficient arc about its vertical center whereby to change the green lenses horizontally centered on said clear lenses to red lenses and to change red lenses horizontally centered on said clear lenses to green lenses which simultaneously changes all green Go signals presented to red Stop signals and vice versa at the completion of the travel of the said yellow Warning signal around the center of each green Go signal.

JOHN J. HAMMER.
